Geo. C. Crane,

Inventor:

John Nesbitt

United States Patent Office.

JOHN NESBITT, OF NORTHFIELD, VERMONT, ASSIGNOR TO HIMSELF AND
LEVI B. TYNG, OF LOWELL, MASSACHUSETTS.

Letter's Patent No. 62,969, dated March 19, 1867.

IMPROVEMENT IN STEAM-ENGINE SLIDE VALVES.

The Schedule referred to in these Letters Patent and making part of the same.

TO ALL WHOM IT MAY CONCERN:

Be it known that I, JOHN NESBITT, of Northfield, county of Washington, and State of Vermont, have invented new and useful Improvements in Balance Valves; and I do hereby declare that the following is a full and exact description thereof, reference being had to the accompanying drawings, and letters of reference marked thereon.

The nature of my invention consists in providing, for a steam chest, a balance valve, to be protected by a shield, for the purpose of keeping the pressure of the steam off of the top of the valve, and allowing the same to work easy in the chest; also with an exhaust port through the valve, for the purpose of letting the exhaust steam from the cylinder escape through the top of the steam chest.

To enable others skilled in the art to make and use my invention, I will proceed to describe its construction and operation.

Figure 1 represents a longitudinal section through the centre of a steam chest, valve, and shield.

Figure 2 represents a plan of a valve with shield face up.

Figure 3 represents an end elevation of a valve with shield.

a represents the cylinder-seat; *b* the steam chest; *c* the steam-chest cover; *d* the valve; *f* the projections for the recesses to receive the metallic packing; *g* and *h* the shield. I propose to obviate and remedy the great pressure of the steam acting upon the top surface of the valves now in use, which pressure oftentimes, with the unclean and foul state of the steam acting on the seat of the valve, produces great friction when working, requiring unnecessary power to operate the same, and resulting in wear and chafing the working surfaces of both valve and cylinder-seats, thus rendering them in a short space of time unserviceable. These objections I believe to a great extent are obviated by my invention. I construct the cylinder, steam chest, and other appendages thereunto belonging, in the usual and ordinary way. I also construct the face or bottom side of my valve in the usual form of slide valves. The top side I construct in various forms, but I prefer the semi-circular form as herein represented, with projections, *ff*; for the reception of the metallic packing *gg*, and an exhaust port *k* through its centre. The top of the valve *d* is turned and finished to a true surface to correspond with the under side of the shield *h*, which is also finished. I make recesses in the top of the projections *ff* on the ends of the valve *d*, in which I place the metallic packing *gg*. I make holes, *ii*, at the bottom of the recesses through the projections *ff* for the steam in the chest *b* to pass through and press against the under side of the packing *gg*, for the purpose of pressing it outward against the under side of the shield *h*. This packing *gg* I make in parts similar to the ordinary packing now used in piston-heads. The shield *h* is made of the requisite length to cover the valve *d* and packing *gg* therein, when the valve *d* is at its extreme points, and is also open at each end, but its sides extend over the valve *d* to the face of the cylinder *a*, upon which it rests, the joints being made steam-tight. The valve *d* does not entirely fill the space between the face of the cylinder *a* and the shield *h*, a small space being provided between the top of the valve *d* and the under side of the shield *h*, which forms a chamber, *ll*, when the packing *gg* in the ends of the valve *d* is pressed outward by the steam against the under side of the shield *h*, thus excluding the steam in the chest from the top of the valve *d*, and thereby shielding the valve *d* from the great downward pressure of the steam in the chest, and allowing the valve *d* to move free and easy under the shield *h*. To prevent the valve *d* from being lifted from its seat by the upward pressure of the steam, in the cylinder ports *oo*, upon its under side, partial provision is made by the chamber *ll* over the valve *d*; this chamber *ll* being filled with the exhausting steam, which enters through the exhaust port *k* in the valve *d*, thus filling the chamber *ll* with the exhaust steam, and applying its pressure upon the top of the valve *d* over its whole area enclosed within the chamber *ll*. This in a measure counterbalances the lifting pressure upon the valve *d* of the steam in the cylinder ports *oo* under the valve *d*, but a further and full provision is made to counteract the lifting force of the steam under the valve *d*, by the downward pressure of the steam in the chest *b*, upon the projection *ff* on the ends of the valve *d*, which contain the packing *gg*, to which may be added any additional area of surface upon the top of the valve *d*, exposed to the downward pressure of the steam in the chest *b*, by inserting the packing *gg* in the valve *d*, at a greater or less distance from the ends of the valve *d*, thus exposing to the pressure of the steam in the chest *b* the necessary

top surface of the valve *d* to counterbalance the upward pressure of the steam in the cylinder ports *o o* under it. The shield *h*, when placed in its position over the valve *d*, is held securely by being screwed down to the face of the cylinder *a*, or by any other convenient method. In cases where the steam chest *b* is short for the slide of the valve *d*, the projections *ff* on the ends may be dispensed with, and the packing *g g* in the valve placed nearer its centre. In some cases it is desirable to exhaust directly through the steam chest. To accomplish this I pass the exhaust pipe *n* through the top of the steam chest *c*, and connect it to the top of the shield *h*, which then has a port, *q*, through it to correspond with the exhaust pipe *n*, and opening to the chamber *ll* over the valve *d*, and to the exhaust port *k* in the valve *d*. The exhaust pipe *n* is screwed through the top of the chest *c* upon a ball-seat, *p*, on top of the shield *h*, where it is firmly held by the nut *r*, binding upon the top of the chest *c*.

What I claim as my invention, and desire to secure by Letters Patent, is—

1. I claim the arrangement of the valve *d*, with reference to the packing *g g*, in its ends, substantially as herein described.
2. I claim the chamber *ll* over the valve *d*, constructed in the manner and for the purpose substantially as herein set forth.
3. I claim the combination and arrangement of the valve *d*, shield *h*, chamber *ll*, and exhaust port *k*, for the purpose substantially as described.
4. I claim the projections *ff*, on the ends of the valve *d*, constructed in the manner and for the purpose substantially as herein described and set forth.

JOHN NESBITT.
